[57] CLAIM

The ornamental design for a wall-mounted golf equipment storage rack, as shown.

DESCRIPTION

FIG. 1 is a top, front perspective view of the wall-mounted golf equipment storage rack showing our new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a side elevational view thereof, the opposite side being a mirror image.

FIG. 2FIG. 3
